ENGINE STARTER

Knute Berger, Seattle, Wash.

Application January 11, 1937, Serial No. 119,938

5 Claims. (Cl. 121—37)

This invention relates to engine starting means, and has for its principal object to provide relatively inexpensive, effective and substantial means for cranking, or starting heavy engines 5 of the Diesel, or other internal combustion types.

More specifically stated, it is the object of the present invention to provide an engine cranking mechanism wherein a rotatably mounted and longitudinally shiftable cranking shaft is axially 10 aligned with the engine shaft and is equipped for a one-way drive clutch connection therewith for the starting operation, and wherein the cranking shaft is operatively connected with the piston of an air cylinder for rotation thereby upon admittance of air under pressure into the air cylinder; the admittance of air to the cylinder being under 15 control of a novel valve mechanism whereby, coincident with the admittance of air pressure and rotation of the cranking shaft, an application of air into another cylinder is effected whereby to move the cranking shaft longitudinally and into a cranking connection with the engine shaft.

It is also an object of this invention to provide, through the above-mentioned valve mechanism, 20 for the application of air pressure into the said cylinder in such manner that an easy engagement of the clutch heads is insured and all detrimental or undesirable impact and strain on the mechanism affected is avoided.

Another object of the invention is to provide 25 means for effecting an automatic return of the parts of the starting device to normal position upon the starting of the engine.

Still another object is to provide means for 30 cushioning the drive of the starting piston at the end of its power stroke.

Other objects of the invention reside in the 35 details of construction and in the combination of parts and in their mode of operation, as will hereinafter be described.

In accomplishing these and other objects of the invention, I have provided the improved details of construction, the preferred forms of which are illustrated in the accompanying drawings, 40 wherein—

Fig. 1 is a view diagrammatically illustrating an engine and a starting or cranking equipment applied thereto in accordance with the present invention.

Fig. 2 is an enlarged detail, partly in section and partly in elevation, of the present engine starting mechanism.

Fig. 2a is an enlarged detail of the double acting valve.

Fig. 3 is an end elevation of the starter mecha-

nism; the control valve being omitted for better illustration.

Fig. 4 is an enlarged, sectional detail on the axial line of the valve mechanism for controlling the application of air pressure for moving the 5 cranking shaft.

Fig. 5 is a cross section on line 5—5 in Fig. 4, showing the valve disk in normal position.

Fig. 6 is a similar view at a reduced scale showing the valve disk in exhaust position. 10

Fig. 7 is an axial section of the air cylinder.

Figs. 8 and 9 are sectional details respectively showing the air relief valve in the cylinder.

Fig. 10 is a detail illustrating an alternative means for returning the parts of the starter to 15 normal position.

Fig. 11 is a section on line 11—11 in Fig. 10.

Referring more in detail to the drawings—

1 designates what may be any one of a number of different types of internal combustion engines, having a crank shaft 2 extended from the engine housing 3; this shaft being the medium through which the present device operates to start the engine. 20

Axially aligned with shaft 2 is the cranking 25 shaft 4 of the starting mechanism embodied by the present invention, and this shaft is revolvably mounted by, and is slidable longitudinally within a bearing 5 which is fixed to, or is formed as a part of a rigid frame structure 6 by which the 30 engine and starting equipment are supported.

At their adjacent ends, the engine shaft 2 and the cranking shaft 4, as shown in Fig. 2, are equipped, respectively, with clutch heads 7 and 8 and these have annular flanges 7' and 8' equipped 35 with ratchet teeth 9 and 10 adapted, by shifting shaft 4 endwise, to be brought into interconnecting contact whereby to provide a one way driving connection between shafts 4 and 2 for starting the engine. 40

Fixed on the shaft 4, at the outer end of bearing 5, is an accelerating sheave wheel 12 through which the shaft may be rotated, as will presently be described, and this wheel is provided in its hub portion 12' with a plurality of inwardly 45 opening sockets 13 in which coiled springs 14 are seated and retained under compression and which springs bear against a disk, or plate 15 disposed against the outer end of bearing 5, thus normally to retain the shaft 4 yieldingly at its outer 50 limit of longitudinal travel at which position the clutch teeth of the parts 7 and 8 are disengaged.

In order to start the engine through the 55 mediacy of shaft 4, it is necessary to bring the clutch heads into interlocked relation and to ro-

tate the shaft. After each cranking operation, it is necessary to effect the return of the cranking shaft to normal position. This and other results are accomplished by the following means:

- 5 Fixedly mounted upon the frame structure 6 which supports the engine, is an air cylinder 18, in which a piston 19 is reciprocally contained. The piston has its rod 20 extended therefrom through a packed gland 21 in an end head 18a 10 closing one end of the cylinder, and this rod is connected at its outer end, as at 22, with a cable 23 which passes about a guide sheave 24 mounted by frame 6 and has its end portion wound upon the sheave wheel 12, and fastened thereto. As 15 will be noted by reference to Fig. 3, the cable 23 leads into the peripheral channel of the sheave 12 at its point of greatest diameter and is fixed to the wheel at the point of shortest diameter. This disposition of the cable provides that, with 20 the piston 19 located at the outer end of its cylinder 18, that being the right-hand end as viewed in Fig. 1 and Fig. 7, should air pressure be applied to the cylinder to drive the piston toward the opposite end thereof, the longer cranking 25 leverage provided through the sheave 12 at the start of the cranking operation will aid greatly in overcoming the inertia in the engine parts. Then, as the wheel 12 is rotated, the gradually decreased effective diameter of the wheel will 30 effect the speeding up of the rotation of the cranking shaft as this inertia is overcome and the rate of travel of piston 19 increases. The arrangement provides also for a relatively slow starting and then a quick acceleration of the 35 cranking shaft that avoids undesirable strains and stresses.

The application of compressed air to the cylinder 18 for starting the engine is under automatic control of a valve mechanism designated 40 in its entirety in Fig. 2 by reference character 25. This mechanism, as seen in detail in Figs. 4 and 5, comprises a valve housing 26 that is fixed solidly in the frame structure 6 in alignment with shaft 4. At its inner end, this valve 45 housing is formed with a cylindrical chamber 27 that is axially aligned with shaft 4 and within which cylinder is slidably fitted an enlarged, piston forming portion 28 at the outer end of the shaft 4. Movement of this piston 28 longitudinally in the cylinder 27 effects a corresponding shifting of shaft 4, and it is this shifting of 50 shaft 4 in opposite directions that effects the engagement and disengagement of the teeth of clutch heads 7 and 8.

55 Formed in the outer end of the valve housing 26 is a pocket 30 that is closed by a cover plate 31 bolted to the housing. A source of compressed air is designated, in Fig. 1, at 35, and this source is connected by a pipe 36, through a valve device 37 and pipe 38, with the closed pocket 30; the pipe 38 communicating with the pocket through the cover plate 31.

The construction of valve 37 is such and it is 60 so connected with the source of air pressure and the cylinder 18, that when in position, it closes the outlet of air from the supply and opens the pipe 38 to atmosphere to exhaust air from the cylinder 18 for return of piston 19 to normal position. When valve 37 is opened, it effects 65 a connection between pipes 36 and 38 for the admittance of air into cylinder 18 to actuate the piston 19 on its power stroke.

As will be noted best by reference to Fig. 4, the pocket 30 had a flat base surface, upon which 70 a flat valve disk 40 is fitted in an air tight con-

nection. The disk has an axial stem, or shaft 41 extended therefrom and revolvably contained in an opening 42 leading into the cylinder 27. This stem extends slidably into an axial bore 43 in the outer end of piston 28. A transverse key 44 fixed in the stem 41 and movable in a longitudinal slot 45 in the piston provides a positive connection between the shaft 4 and valve disk 40 whereby the disk is rotated in accordance with rotation of the shaft 4, but relative longitudinal movement of shaft 4 is permitted on stem 41.

The valve disk 40 is held tightly seated by means of a coiled spring 59 that is confined under compression in an axial socket 51 in the outer face of the disk and bears, at its outer end, against a ball 52 which, in turn seats against the cover plate 31.

Formed through the valve disk, and extending through an angle of approximately 135° about 20 the disk center is an arcuate slot 60. When the disk is in its normal position, as just prior to an application of starting air, one end of this slot 60 just slightly overlaps a port or channel 62 which is formed in the valve housing and 25 which provides a connection with a pipe 64 leading to the outer end of the air cylinder 18. Thus when air pressure is applied to the pocket 30, it is communicated through the arcuate slot 60, port or channel 62 and pipe 64 into one end of 30 the cylinder 18 and actuates the piston toward the opposite end. The arcuate slot 60 is of such extent that it will maintain communication between the source of air pressure and cylinder 18 throughout the travel of the piston and the 35 resultant rotative movement of the shaft 4 and valve disk. By reason of the opening that is provided by the slot 60, just slightly overlapping the port 62, flow of air under pressure to the cylinder 18 will be initially restricted to such extent 40 that the piston 28 will be actuated to engage the clutch heads 7 and 8 prior to the application of air pressure to the cylinder 18 for effecting the rotary action of the shaft 4.

It will be observed also that there is a port 45 70 formed directly through the upper part of the disk, as shown in Fig. 5, and that this, when the parts are in normal position and at the start of an operation, has direct registration with a port 71 in housing 26 leading into the inner end of cylinder 27. Thus, coincident with the application of air to the cylinder 18, there will be an application of air under pressure into cylinder 27, thereby to overcome the pressure of springs 13 and to move the piston 28 and shaft 4 longitudinally, thus to cause the teeth of clutch heads 7 and 8 to be operatively engaged.

It will now be understood that, resultant to the application of air into pocket 30 by opening valve 37, there will be effected a movement of piston 18 whereby, through the mediacy of cable 23 and sheave 12, the shaft 4 will be rotated, and also, by reason of longitudinal shifting of shaft 4, that the clutch heads will be engaged so that the rotation of shaft 4 will effect the driving of the engine shaft 2 for the starting or cranking operation.

By reason of the fact that the registering openings 70 and 71 will provide a direct passage 70 for compressed air admitted to the pocket 30 into the cylinder 27, and because the springs 14 afford less resistance to shifting of the shaft 4 than is afforded to the actuation of the cranking mechanism by spring 85, the piston 28 will be actuated inwardly to engage the clutch head 75

8 with the clutch head 7 before there is any rotation of the crank shaft effected by the action of the compressed air admitted to cylinder 18.

5 Referring again to Figs. 4 and 5, it will be noted that there is a relatively short arcuate groove or channel 15 formed in the under surface of the valve disk about the disk axis which, shortly after the valve disk starts to rotate by 10 reason of application of air pressure into cylinder 18, will move into a position at which it serves as a communicating passage between the port 11 and an air exhaust port 18 opening upwardly to atmosphere through the valve housing 15 wall. This provides that, after the clutch heads have been engaged for starting the engine, and after power has been applied for rotating the shaft 4, air will be exhausted from cylinder 21 and thus just as soon as driving contact between 20 the teeth of the two clutch heads is relieved, the shaft 4 will be shifted outwardly by the action of the springs 13, and the clutches thus disengaged. This driving contact which holds the ratchet teeth of the clutches engaged will be relieved either by 25 reason of the starting of the engine under its own power and turning at a faster rate than the cranking shaft, or by reason of the piston 19 reaching its limit of travel.

As soon as the piston 19 reaches its limit of travel in cylinder 18, the operator closes valve 37, and thus, as was previously explained, air is exhausted from the power end of cylinder 18, and the piston is returned to normal position and ready for another starting operation by means of a coiled spring 25 which is fixed at one end to frame 6 and is attached, under tension, at its other end to a cable 86, which leads over a sheave 87 onto the sheave 12 and is wound thereon in a direction opposite to cable 23 and is attached thereto.

40 In Figs. 10 and 11 an alternative means for returning the shaft 4 to normal position is shown. In this, a helical spring 89 is applied to the sheave and has opposite ends connected, respectively, to the sheave as at 91 in Fig. 10, and to a 45 pin 90 fixed in frame 6.

In order that the drive of piston 19 in cylinder 18 may be cushioned on reaching the outer limit of its travel, an air cushion valve mechanism is provided in the cylinder, as will best be understood by reference to Figs. 7, 8 and 9. This valve mechanism comprises a tubular valve stem 92 that is slidably fitted in an axial bore 93 in the cylinder end head 18b. This stem has a valve head 94 at its inner end adapted to close over a 55 pocket 95 formed in the inner face of the head 18a about the stem 92, and from which pocket ports 96 open to atmosphere. A coiled spring 97, seated in the pocket and bearing against the valve head, holds the valve yieldingly in open 60 position. The inward opening travel of the valve stem is limited by a collar 99 fixed about the stem in a position to engage the end wall 18a. Normally the valve is in the open position, as seen in Fig. 9.

65 Slidably fitted inside of the tubular valve stem 92 is a stem 105. This projects through an inner end opening 106 in stem 92 a substantial distance into the cylinder, and is normally held yieldingly in extended position, as in Fig. 9, by a coiled 70 spring 107 that is disposed inside of valve tube 92 between the inner end of the stem 105 and a plug 108 that closes the outer end of the tubular stem 92. For reasons presently apparent, the spring 107 is stronger than spring 97.

75 When the piston 19 moves on the power stroke

under influence of compressed air admitted through pipe 64, it causes a ready exhaustion of air from the cylinder end through the pocket 95 and ports 96. However, as the piston nears its limit of travel, it engages the inner end of stem 105, and pushes it, together with stem 92 outwardly, thereby closing the valve head 94 against its seat, and thereby cuts off escape of air to atmosphere. The trapped air then forms a cushion whereby the travel of piston 19 is retarded and 10 finally checked without detrimental impact. As the piston 19 returns to normal position, the stem 105 returns to normal position in stem 92, and valve 94 moves to open position under influence of spring 97.

15 Devices of this character are especially useful for heavy Diesel engines, but may be used on various other types with satisfaction. The mechanism is relatively inexpensive, easy to apply, substantial and will operate effectively for the intended purpose.

Having thus described my invention, what I claim as new therein and desire to secure by Letters Patent is:

20 1. The combination with an engine having a starting shaft equipped with a clutch head with teeth of the ratchet type, of an engine starting means comprising a revolubly mounted cranking shaft having a clutch head formed with teeth of ratchet type opposingly faced to those of the clutch head first mentioned; said cranking shaft disposed coaxially of the starting shaft, said clutch heads being fixed on adjacent ends of their respective shafts and normally disengaged, and said cranking shaft being adapted to be shifted 25 in its mounting from a neutral position toward the said starting shaft to effect a one-way holding and driving connection between the said clutch heads for a starting operation, a common source of power for both the shifting and rotating 30 movements of the cranking shaft, means for applying the power to effect a shifting of the cranking shaft, power actuated means for rotating the cranking shaft, for a starting operation, means operable to delay the application of power to the 35 means for rotating the cranking shaft until after the cranking shaft has been shifted to engage the starting shaft, means for terminating the application of shifting power to the cranking shaft 40 after rotation has begun, and spring means acting against the cranking shaft to shift it to neutral position when the driving connection becomes 45 ineffective.

2. The combination with an engine having a starting shaft provided with a clutch head formed with ratchet teeth, of an engine starting means comprising a revolubly mounted cranking shaft having a clutch head formed with ratchet teeth opposing those of the first mentioned clutch head, and adapted to be shifted in its mounting 55 to effect a one-way driving connection between the said teeth of the clutch heads for a starting operation, normally inactive means for rotating the cranking shaft for a starting operation, means for admitting a fluid pressure medium to said 60 normally inactive means for energizing it, and means acted on by said pressure medium for moving the cranking shaft to operatively engage the teeth of the clutch heads; said fluid pressure admitting means being operable to delay the admitting of the pressure medium to the normally inactive means for rotating said cranking shaft until after the latter has been shifted to engage the said starting shaft and also operable to terminate and to relieve the application of shifting 65 70 75

- power to the cranking shaft after rotation has begun, and means acting against the cranking shaft to return the latter to neutral position when the driving connection becomes ineffective, and yieldable means for returning the normally inactive rotating means to initial position on completion of the starting cycle.
3. In combination, an engine having a crank shaft and a starting mechanism for the engine, comprising a cranking shaft revolubly mounted and axially shiftable in its mounting between neutral position and a position at which it effects an operative connection with the crank shaft for starting the engine, a cylinder reciprocally containing one end of said cranking shaft therein as a piston, a power cylinder, a piston in the power cylinder, means connecting the latter piston with the cranking shaft whereby a power stroke of the piston effects rotation of the cranking shaft, a source of pressure medium and a distributing valve device through which said pressure medium may be administered to the cylinders to move the pistons therein to give the cranking shaft a rotating impulse and to shift the same axially to effect a starting connection with the engine shaft, means operable automatically to shift the cranking shaft to neutral position when the cranking impulse becomes ineffective; said distributing valve comprising a valve member operatively connected with the cranking shaft for rotation thereby, and operable incident to rotation, to effect the exhausting of pressure medium from the second mentioned cylinder after cranking connection has been effected.
35. 4. In combination, an engine crank shaft having a clutch jaw, an engine cranking shaft axially aligned therewith and having a clutch jaw at its inner end adapted to be engaged with the clutch jaw of the crank shaft to effect a releasable cranking connection, a power cylinder having a piston, means operatively connecting the piston with the cranking shaft whereby an outward travel of the piston will rotate the cranking shaft for starting the engine, a cylinder operatively containing the outer end portion of the cranking shaft as a piston, a distributor valve having a connection with a source of pressure medium and also separate connections therethrough with both of said cylinders whereby the pressure medium may be administered to both cylinders; said connection through the distributing valve to the cranking shaft cylinder being normally open and unrestricted and adapted to be closed to the source of pressure and subsequently opened to atmospheric pressure, and the said connection to the power cylinder being normally in a restricted

condition to delay the application of pressure medium to the power cylinder to allow the cranking shaft to move axially toward the engine crank shaft to effect a cranking connection through their respective clutches before the power piston is actuated to rotate the cranking shaft, and means for exhausting pressure medium from the power cylinder for the return of its piston to starting position, and yieldable spring actuated means for automatically returning the power piston upon the exhausting of the pressure medium.

5. The combination with an engine having a starting shaft, of a starting mechanism comprising a revolubly mounted cranking shaft axially aligned with the starting shaft and axially shiftable in its mounting from a neutral position to a position at which its inner end effects an operative driving connection with the starting shaft, a piston on the outer end of the cranking shaft, a fixed cylinder within which the cranking shaft piston is reciprocally mounted, a source of fluid pressure medium, a distributing valve mechanism comprising a housing, a valve member rotatable by the cranking shaft, a fluid connection between the source of pressure medium and the valve housing, a normally closed double action valve in the connection permitting the valve housing to be open to the atmosphere when closed to the source of pressure medium, a fluid connection between the said valve housing and the cranking shaft cylinder, a port in said distributing valve member normally open to the connection between said valve housing and said cranking shaft cylinder providing for the application of pressure medium for shifting the cranking shaft, and maintaining said shifting pressure during rotation of the cranking shaft, a second port in the valve member adapted to relieve pressure within said shifting cylinder to the atmosphere before completion of the rotary motion of the said valve member, an eccentric accelerating sheave fixed on the cranking shaft, a power cylinder having a reciprocating piston mounted therein, a cable connection between said piston and said eccentric accelerating sheave for starting the engine, a fluid connection between the power cylinder and the distributing housing, and a port in the distributing valve member partially restricting this connection but adapted to relieve this restriction as the cranking shaft is rotated, and a yieldable spring means for returning the power piston to its initial position upon relieving of the pressure in the cylinder through the said double acting valve.

KNUTE BERGER. 55
